No. 36,559.

Patented September 15, 1903.

UNITED STATES PATENT OFFICE.

FRANK D. WHITE, OF AKRON, OHIO.

DESIGN FOR A FLOOR OR WALL COVERING.

SPECIFICATION forming part of Design No. 36,559, dated September 15, 1903.

Application filed August 12, 1903. Serial No. 169,299. Term of patent 14 years.

To all whom it may concern:

Be it known that I, FRANK D. WHITE, a citizen of the United States, residing at Akron, in the county of Summit and State of Ohio, have 5 invented a new, original, and ornamental Design for a Floor or Wall Covering, of which the following is a specification, reference being had to the accompanying drawing, forming a part hereof.

10 The drawing presented represents a plan view of my design.

What I claim, and desire to secure by Letters Patent, is—

The ornamental design for a floor or wall covering, as shown.

In testimony whereof I have signed my name to this specification in the presence of two subscribing witnesses.

FRANK D. WHITE.

In presence of—

C. E. HUMPHREY,
BESSIE CROOK.
